UNITED STATES PATENT OFFICE.

RICHARD T. GRIFFITHS, OF AKRON, OHIO.

DESIGN FOR AN OVERSHOE.

Application filed April 4, 1929. Serial No. 30,755. Term of patent 14 years.

To all whom it may concern:

Be it known that I, RICHARD T. GRIFFITHS, a citizen of the United States, residing at Akron, in the county of Summit and State of Ohio, have invented a new, original, and ornamental Design for an Overshoe, of which the following is a specification, reference being had to the accompanying drawing, forming part thereof,

Fig. 2 is a front view, and

Fig. 3 is a side elevation of the right side of an overshoe.

I claim:

The ornamental design for an overshoe, as shown.

RICHARD T. GRIFFITHS.
